COMBINED GRIDDLE AND COVER

Robert O. Ernest, Oak Park, Ill., assignor to Sunbeam
Corporation, Chicago, Ill., a corporation of Illinois

Filed Sept. 17, 1958, Ser. No. 52,665

Term of patent 14 years

(Cl. D81—10)

FIG. 4.

6. +

FIG. 5.

FIG. 6.

Fig. 1 is a top perspective view of a combined griddle and cover embodying my design;

Fig. 2 is a front elevational view thereof;

Fig. 3 is a rear elevational view thereof;

Fig. 4 is a top plan view thereof;

Fig. 5 is a side elevational view thereof; and

Fig. 6 is a fragmentary sectional view taken along line 6—6 of Fig. 4.

I claim:

The ornamental design for a combined griddle and cover, as shown.
